UNITED STATES PATENT OFFICE.

MARTIN F. MERIFIELD, OF HICKSVILLE, OHIO.

BABY SWING.

1,418,318.

Specification of Letters Patent. Patented June 6, 1922.

Application filed November 29, 1921. Serial No. 518,225.

To all whom it may concern:

Be it known that MARTIN F. MERIFIELD, citizen of the United States, residing at Hicksville, in the county of Defiance and State of Ohio, has invented certain new and useful Improvements in Baby Swings, of which the following is a specification, reference being had therein to the accompanying drawing.

10 The present invention relates to baby swings, or cradles, and has for its object to produce a collapsible baby swing which can be readily and cheaply manufactured, which can be taken apart and put together with 15 great facility without the aid of tools, and which in collapsed condition can be disposed in a small compact space for convenient storage, shipment, or handling.

Referring to the accompanying drawings 20 for a detailed description of a swing embodying the invention,

Figure 1 is a side elevation of the swing and its supporting frame in assembled, or operative, position. Figure 2 is an exploded view of the swing, that is, a view 25 showing the parts disconnected; and Figure 3 is a similar view of the swing support.

The swing is composed of a support designated generally by the numeral 1, and a 30 cradle 2, these parts being composed preferably of wood.

The support 1 consists of end frames 3 connected by side bars 4, in the manner clearly indicated by Figures 1 and 3. As 35 here shown, the end frames 3 have on each side thereof a pair of vertically spaced plates covering recesses cut in the frames adjacent the lower end thereof and having a key hole 5 for the reception of headed bolts 6 which 40 project from each end of the side bars, so that when the heads of said bolts are passed through the upper circular parts of the key holes and the side bars moved downward, the said bars and frames are locked against 45 horizontal displacement. To lock the parts against vertical displacement, there is provided a slot or recess 7 below each pair of key holes and a turn button 8 mounted on the under side of bars 4 adjacent each end 50 thereof, whereby when the turn buttons are rotated into alinement with the side bars, the outer ends of said buttons project into the recess 7 and so lock the side bars and end frames securely together.

55 The cradle 2 consists of a bottom board or plate 9 of a general rectangular form, end

boards 10, and side boards 11. The end boards, as clearly indicated by Figs. 1 and 2, are connected by hinges 12 to the bottom board, so that when the parts are disassembled the end boards can be folded back and over on the under face of the bottom board 60 9 in parallel relation thereto. The end boards are furnished with vertically spaced plates having key holes and covering suitably recesses cut therein, and the side boards have headed bolts adapted to enter said key holes and to slide therein so as to lock said boards in assembled position. To prevent vertical displacement of the side boards, 70 turn buttons 15 are mounted on the lower edges of said boards so as to contact the under side of the bottom board when turned at an angle to the planes of said side boards. 75

The cradle may be supported on frame 1 by means of V-shaped bails 16, which are hung over bolts 17 attached to the upper ends of said frame. The parts may be of any suitable design and painted or enameled as desired. 80

It will be apparent from the above description that the baby swing embodying my invention is of simple yet rugged construction, comprising parts which can be manufactured in quantity lots and at a comparatively small cost. Any one of ordinary mechanical aptitude can readily take the swing apart and put it together with little effort. When the swing is disassembled, the parts constituting the same may be arranged in a 90 flat compact bundle which can be conveniently carried about in an ordinary blanket or book strap. 85

Having particularly described an embodiment of my invention without thereby intending to limit myself to the exact details shown, what I claim as new and desire to secure by Letters Patent of the United States is:

1. A collapsible baby swing consisting of 100 a supporting frame including side and end pieces, said end pieces each having key slots cut in their inner faces adjacent the lower ends thereof and said side pieces having headed bolts projecting from their ends and 105 adapted to slidably engage said slots and said side pieces having turn buttons on their lower faces adapted to project into said recesses and lock the parts in assembled position, and a cradle swung from the upper 110 ends of said end pieces composed of bottom, end and side members, hinges connecting the.

bottom and end members to permit the end members to be folded flat against the surface of the bottom member, said end members having key slots cut in their inner faces 5 and said side members having headed bolts projecting from their ends and adapted to slidably engage said key slots, and said side members having turn buttons adapted to be turned into engagement with the under surface of said bottom member.

2. In a collapsible baby swing, a cradle composed of bottom, end, and side boards, hinges connecting the bottom and end

boards, to permit the end boards to be folded flat against the surface of the bottom board, 15 said end boards having key slots cut in their inner faces and said side boards having headed bolts projecting from their ends and adapted to slidably engage said key slots, and said side boards having turn buttons 20 mounted on their lower edges adapted to be turned into engagement with the under surface of said bottom board.

In testimony whereof I hereunto affix my signature.

MARTIN F. MERIFIELD.
